UNITED STATES PATENT OFFICE.

ARBA G. WILLIAMSON, OF CARNEGIE, PENNSYLVANIA, ASSIGNOR TO PITTSBURGH TRAIN CONTROL COMPANY, OF PITTSBURGH, PENNSYLVANIA, A CORPORATION OF DELAWARE.

TRACK-CIRCUIT SYSTEM.

Application filed April 5, 1922, Serial No. 549,662. Renewed February 3, 1922.

This invention relates to track circuit systems particularly for use in connection with train control systems of the type disclosed in application Ser. No. 555,304, filed

5 April 18, 1922.

In systems of the character indicated in those applications the train is provided with two pick-up circuits one of the indirect type and the other of the direct type and the 10 main object of this invention is to provide means whereby a circuit may be established including both rails of a block and whereby also another circuit may be established between one or both rails and ground to properly coordinate the indirect and direct pick-up circuits on the train with track equipment. By "indirect" pick-up circuit is meant a circuit on the train in inductive relation to the current in the rails and by "direct" 15 pick-up circuit is meant a circuit on the train of an electrostatic character, that is: there is a device in the train in circuit with one or more rails and having a capacity between itself and ground.

20 A further object of the invention is to provide means whereby the circuit between one rail and ground is so arranged that existing track circuits may be used with but slight alteration.

25 Other features of the invention will appear as the specification proceeds.

The broad features of this invention are claimed in application Ser. No. 549,661, filed April 5, 1922, one of the specific forms shown 30 in that application being the subject matter of this application.

In the accompanying drawing the invention is shown diagrammatically in two preferred forms as part of a standard track 35 circuit, Fig. 1 showing the track equipment controlled by the signals and Fig. 2 showing the track equipment controlled by a relay.

Referring to Fig. 1, 1 and 2 represent the rails of a traffic track divided into blocks, 40 W, X, Y and Z in a manner well understood as by means of insulation 3. 4 and 5 indicate line wires fed by a single frequency generator G. Associated with each block is a main transformer indicated by T_w , T_x and T_y and the secondary 6 of each of these 45 transformers is connected by means of conductors 7 and 9 with a primary 8 of a track transformer indicated variously as N_w , N_x and N_y . Thus secondary 6, conductor 7, pri-

mary 8 and conductor 9 constitute what may 50 be called an intermediate circuit. Secondary 13 of the track transformer is connected by suitable leads with rails 1 and 2 thereby supplying current to both of said rails of a given block. Interposed between secondary 6 of the main transformer and primary 8 of the track transformer is a circuit breaker in the form of a pole changer P_w , P_x and P_y and connected to wire 7 between the pole changer and secondary 6 is conductor 101, 55 impedance 102, and wire 103 grounded at 104. Also connected between wires 7 and 14 is a shunt 105 around the track transformer. The pole changer may be controlled either 60 from a signal or a relay. In this case, it is controlled from the signal and a relay, L_w , L_y and L_z which is of the two element type being influenced both by the track circuit and by current from transformer T in 65 a manner to be presently described. Q indicates a winding affecting relay L, this winding being connected to wires 7 and 9 and therefore fed by transformer T. Accordingly one element of relay L receives 70 current from the track circuit and the other element Q from the main transformer. It is well known that when the instantaneous polarity of both elements is such that the currents in both elements are in phase then 75 armature 100 will swing to right hand position. If the connections of one element should be reversed so that the instantaneous polarity of the currents in the two elements are out of phase then armature 100 will swing to the left hand position. If current 80 is absent in the track element then armature 100 will hang in center position. Reversal of the instantaneous polarity of the current in the track rails is accomplished by the pole changer reversing the connections to 85 the primary of the track transformer, the pole changer being here operated by the signal mechanism as indicated by dotted line A. It is further well known that when signal 90 S_z is a stop or danger position then pole changer P_y is moved to the left hand position, in which position the instantaneous polarity of the current in rails of block Y is out of phase with that of element Q_y and armature 100 of relay L_y will therefore 95 assume its left hand position and signal S_y will therefore assume caution position. Signal S_y when moving into caution position 100

105

will move pole changer P_x from left to right hand position, and the polarity of the current in the rails of block X being now such in respect to element Q_x that armature 100 of relay L_x will assume its right hand position and therefore signal S_x will move to clear. When this occurs signal S_x will not move pole changer P_w to any new position but said pole changer will occupy the same position as it did under caution conditions. Assuming now that a train proceeds in the direction indicated by the arrow, it will be understood that so long as current is flowing in the track circuit the indirect pick-up circuit on the train will be influenced and it is only when a train enters a block such as Z, already occupied by another train, that the indirect pick-up circuit is not influenced by the track circuit.

When a train K occupies block Z then pole changer P_x will occupy its right hand position and current from secondary 6 of transformer T_x will be supplied to the rail and ground circuit as follows: secondary 6, conductor 7, conductor 101, impedance 102, conductor 103, ground 104, rail 1, conductor 14, shunt 105, conductor 7, pole changer P_x , conductor 9, and back to secondary 6. Rail 1 is not grounded but may in fact be insulated from ground. That is to say the insulation is of course not perfect and there exists a leakage of current but not excessive so that voltage above ground potential is maintained on the rail. If the rail was actually grounded it would not be possible to maintain this voltage and consequently the direct pick-up circuit would not receive an impulse. The direct pick-up circuit of a train entering block X will therefore be influenced. In block Y, however, pole changer P_y is in the left hand position and therefore that side of secondary 6 of transformer T_y which is connected to ground is also connected to rail 1 of block Y and therefore no current from secondary 6 flows through the rail and ground circuit. Therefore the direct pick-up circuit of the train will not be influenced.

In Fig. 2 the signal control is omitted and an additional relay 150 is interposed which relay controls the pole changer, and is controlled by armature 100. Relay 150 is energized by connecting one wire 151 to wire 9, connecting armature 100 to wire 7 of the intermediate circuit and providing two contacts 152 and 153 connected to relay 150. It will be seen that when relay L_x is deenergized its armature 100 will drop thereby rupturing circuit through relay 150₂ and causing current of one polarity to be supplied to the track transformer by means of pole changer P_y and also cutting out the rail and ground circuit. This energizes relay L_y causing its armature to swing to the left into engagement with 152 thereby estab-

lishing a circuit through relay 150₂ and causing pole changer P_y to supply current of the opposite polarity to track transformer N_y and at the same time establishing the rail and ground circuit. This in turn energizes relay L_x to move its armature 100 to the right against contact 153 thereby supplying current of the same polarity to block W and maintaining the rail and ground circuit intact. 75

The arrangement shown in Figure 2 of the drawings hereof is not claimed specifically in the present application, but forms the subject matter of another application filed August 16, 1928, Ser. No. 299,885. 80

I claim:

1. A track circuit system comprising: traffic rails divided into blocks, a circuit including both rails of a block, a circuit between ground and at least one of said rails for maintaining voltage above ground potential on at least one of said rails, and a pole changer controlled from a preceding block and controlling both circuits of the local block. 85

2. A track circuit system comprising: traffic rails divided into blocks, a circuit including both rails of a block, a circuit between ground and at least one of said rails for maintaining voltage above ground potential on at least one of said rails, and a pole changer controlled from a preceding block and controlling both circuits of the local block and a pole changer of a succeeding block. 90

3. A track circuit system comprising: traffic rails divided into blocks, a track circuit including both rails of a block, an intermediate circuit, a main circuit, a transformer between the main and intermediate circuits, a track transformer between the intermediate and track circuit, a pole changer in the intermediate circuit, a shunt around the track transformer and connecting the intermediate and track circuits, and a ground connection in the intermediate circuit between the pole changer and the main transformer. 10

4. A track circuit system comprising: traffic rails divided into blocks, a track circuit including both rails of a block, an intermediate circuit, a main circuit, a transformer between the main and intermediate circuits, a track transformer between the intermediate and track circuits, a pole changer in the intermediate circuit, a shunt around the track transformer and connecting the intermediate and track circuits, a ground connection in the intermediate circuit between the pole changer and the main transformer, and a two element relay, one element of which is included in the track circuit and the other element of which is controlled from the main transformer of a succeeding block. 11

5. A track circuit system comprising:

traffic rails divided into blocks, a track circuit including both rails of a block, an intermediate circuit, a main circuit, a transformer between the main and intermediate circuits, a track transformer between the intermediate and track circuits, a shunt around the track transformer and connecting the intermediate and track circuits, a ground connection in the intermediate circuit, and a pole changer controlling the polarity of the track circuit and acting to include or exclude the main transformer between the shunt and the ground connection.

6. A track circuit system comprising: traffic rails divided into blocks, a track circuit including both rails of a block, an intermediate circuit, a main circuit, a transformer between the main and intermediate circuits, a track transformer between the intermediate and track circuits, a shunt

around the track transformer and connecting the intermediate and track circuits, a ground connection in the intermediate circuit, a two element relay one element of which is included in the track circuit and the other element of which is controlled from the main transformer of a succeeding block, a pole changer controlling the polarity of the track circuit and thereby the two element relay of a local block and acting also to include or exclude the main transformer between the shunt and the ground connection, said pole changer being controlled from the two element relay of a preceding block. 25

Signed at Pittsburgh, in the county of Allegheny and State of Pennsylvania this 30th day of March 1922. 30
